(57) CLAIM

The ornamental design for a basketball rim ball blocker, as shown and described.

DESCRIPTION

FIG. 1 is a front elevational view of a basketball rim ball blocker showing my new design;

FIG. 2 is a rear elevational view thereof;

FIG. 3 is a bottom plan view thereof;

FIG. 4 is a top plan view thereof;

FIG. 5 is a top perspective view thereof; and,

FIG. 6 is an enlarged portion as designated in FIG. 1 view. The broken lines in the drawings depict portions of the basketball rim ball blocker that form no part of the claimed design.
